UNITED STATES PATENT OFFICE.

LEWIS M. KEIZER, OF BALTIMORE, MARYLAND.

CARBURETER.

1,125,338.

Specification of Letters Patent. Patented Jan. 19, 1915.

Application filed February 24, 1911. Serial No. 610,542.

To all whom it may concern:

Be it known that I, LEWIS M. KEIZER, a citizen of the United States of America, residing at the city of Baltimore, State of Maryland, have invented certain new and useful Improvements in Carbureters for Internal-Combustion Engines, of which the following is a specification.

This invention relates to carbureters for internal combustion engines, and particularly to the type of carbureter which consists of an air passage in which liquid fuel is presented to an air current.

The carbureter of my invention consists of an air passage, a fuel delivery therein, a fuel valve, a valve for controlling the air passage, operating means for the two valves connecting them and moving them together, and independent means for adjusting the operating means whereby the motion of one valve relatively to the other may be varied. Such variation is preferably accomplished without changing the lead of the fuel valve.

An important feature of my invention consists in an adjustment of the fuel valve relatively to the operating means to determine its lead.

In the carbureter herein shown and described, and in connection with which my invention has been reduced to practice, the fuel valve is controlled by means of a cam, and the throw of this cam may be adjusted to vary the movement of the fuel valve relatively to that of the throttle.

In the preferred form of my invention the cam is pivoted to swing, the pivot being transverse to the throw of the fuel valve. The latter is provided with a follower which coöperates with the cam to open and close the fuel valve as the throttle or air valve is opened and closed, the cam follower being so placed that at low throttle when the fuel valve is in its initial position, the follower is over the cam pivot. The cam face is preferably concentric with the pivot at this point so that adjustment of the cam does not vary the lead of the fuel valve. When the carbureter is used on motor cars, it often happens as in climbing hills, etc., that while speed is reduced increased pressure in the cylinder and hence a richer mixture is desired. But under these circumstances, if the air valve and fuel valve are opened correspondingly, the speed of the

air is reduced and the mixture is weakened. To provide for these conditions, I supply means for temporarily raising the cam to give an increased opening of the fuel valve.

In the construction of my carbureter I have found it desirable to divide the entering air into two currents of which one only comes in contact with the fuel nozzle and acts as a vehicle for the hydrocarbon. The two currents are later combined and mixed before entering the engine cylinder. For convenience, these two currents may be referred to as primary and secondary air, respectively. At low throttle the secondary air is preferably cut off or largely reduced. By thus dividing the air passage and placing the fuel nozzle or delivery in one of the two air passages, and cutting off the flow to the other passage at low throttle, I am enabled to secure a sufficient flow in the vicinity of the nozzle at low throttle to maintain the mixture substantially constant. At high speed or open throttle the increased current by the nozzle is sufficient to take up enough hydrocarbon to still maintain the mixture constant when the air thus carbureted is combined with that flowing through the secondary air passage. In the carbureter which I have shown and described, the throttle valve and the valve controlling the secondary air passage are formed integral. However, the air and throttle valve may be differently arranged within the scope of my invention, and the combined current may be differently controlled.

A carbureter embodying various features of my invention in its preferred form is shown in the accompanying drawings:

Figure 1 is a vertical axial cross-section through the carbureter taken on the line 1, 1 of Fig. 2. Fig. 2 is a plan. Fig. 3 is a vertical axial cross-section through the valve chamber and air passages taken on the line 3, 3 of Fig. 4. Fig. 4 is a fragmentary horizontal section on the line 4, 4 of Fig. 3. Fig. 5 is a fragmentary elevation of the carbureter looking from the direction of the air inlet. Fig. 6 is a top plan view of the float valve; Fig. 7 is an elevation of the carbureter.

The carbureter shown in the drawings consists of an air passage 1 in which is a

fuel delivery device or nozzle 2. As shown, the air passage comprises a mixing chamber 3, a primary air inlet 4 which terminates in a hood 5 surrounding the nozzle and delivering into the chamber 3, a secondary air inlet 6 to the mixing chamber and a delivery passage 7. The intake end of the air passage 1 is preferably circular, as shown, and though divided into two passages 4 and 6, is 10 adapted to be served by a single pipe and a single current of air which is divided at the mouths of the passages 4 and 6. Within the mixing chamber 3, the walls of which as shown are cylindrical, is a valve member 8 15 also cylindrical in form and fitting the cylindrical walls 9 of the chamber. The valve 8 has inlet and outlet openings 10 and 11 registering with the secondary air inlet and the delivery, respectively. The delivery valve opening 11 is formed with a lead notch 12, and the openings 10 and 11 are so placed that when the fuel opening 11 registers with the delivery 7, the valve opening 10 registers with the secondary inlet 6 so that the air 20 passage 1 is free in all its branches and the maximum current of air is flowing through the carburetor. When the valve 8 is rotated so that the opening 11 is moved out of registration with the delivery 7, the lead notch 25 12 is opened by being brought over the delivery and the secondary inlet 6 is closed, the opening 10 being moved out of registration. To limit the oscillation of the valve as described, the cover 13 of the chamber 3 is provided with stops 14, and the cylinder or 30 barrel-valve 8 is provided with coöperating stops 15. The hood 5 is preferably carried by the barrel-valve 8 integral with its bottom wall 16 or attached thereto, so that the hood may be removed with the barrel to 35 permit inspection of the nozzle when setting the level of the liquid. The hood has an outlet opening 17 disposed toward the delivery valve opening 11. It will be noted that the free area of the hood in the horizontal plane of the nozzle opening is substantially equal to the area of the primary air inlet 4, and that the combined areas of the inlets 4 and 6 are substantially equal to the area of the delivery 7. In this way the 40 speed of the air flowing through the carburetor is maintained as nearly uniform at the different points of its path as possible, and loss of speed and power from eddying and unnecessary friction are in a large measure avoided. The valve 8 is provided with a neck 18 axially placed and extending upward through the cover 13. Secured to the neck by means of a split collar 19 is a horizontal hand lever 20. Pivotaly mounted on the lever 20 to swing in a radial plane of the axis of the barrel-valve 8 is the fuel valve lever 21. Threaded in the nut 22 which is mounted on trunnions 23 in the fuel 45 valve lever 21 is the fuel valve 24. This is

shown in the form of a needle valve which passes downward through a central vertical opening 25 in the neck 18 of the barrel-valve and engages a seat 26 in the tip of the nozzle 2.

The upper end of the stem 28 of the valve 24 has a knurled head 29 for manual adjustment, and a lock-nut 30 is provided for maintaining the valve in adjustment. It will be apparent that when the fuel valve lever 21 is supported by any suitable means as hereinafter described, the fuel valve may be adjusted up and down by turning it in the trunnion nut 22.

Mounted on the cover 13 is a fuel valve 80 actuating device shown in the form of a cam 31. This is pivotally mounted at 32 to swing up and down. The cam 31 is adjusted about its pivot 32 by means of a screw 33 threaded in a lug 34 carried by the cam and bearing 85 against a suitable abutment 35 on the cover 13. A second arm 36 of the lever 20 carries near its extremity uprights 37, one on each side of the fuel valve lever 21. Supported on the upper extremity of these uprights is 90 a nut 38 in which is threaded a hollow screw-cap 39 within which is a compression spring 40 bearing downward against the top of the fuel valve lever 21. At the extremity of the lever 21 is a follower 41 engaging the cam 95 31 and maintained in contact therewith by the action of the spring 40.

It will be apparent that as the barrel-valve is oscillated by manual operation of the lever 20 or otherwise, the follower 41 100 will be moved over the cam 31, and the fuel valve 24 opened and closed, and preferably the parts are so arranged relatively to each other that at low throttle the follower 41 bears on the surface of the cam adjacent the 105 pivot 32 and preferably the cam surface at this point is constructed in the form of an arc concentric with the pivot. Therefore the fuel valve opening or lead at low throttle is constant except for the adjustment described, relatively to the lever 21 by means of the nut 22. As the valve 8 is rotated and the throttle and secondary air inlet openings increased toward maximum, the fuel 110 valve is opened by the action of the cam, and fuel in proportion to the air is supplied.

Under certain circumstances which occur comparatively infrequently, as changes of season, etc., requiring variation in the richness of the mixture, it is found desirable to 120 adjust the ratio of the openings of the fuel and throttle or air inlet valve. To accomplish this I turn the cam about its pivot 32 by means of the screw 33 or otherwise vary the throw of the cam. In this connection it 125 is important to note that under all adjustments of the cam, the initial opening of the fuel valve is constant as rotation of the cam about its pivot 32 does not affect the position of the cam follower 41.

In hill climbing it frequently becomes necessary to temporarily increase the opening of the fuel valve beyond that given by the cam 31. This is to develop greater power at somewhat reduced speed, and it may be accomplished in various ways. I have provided an oscillating wedge or cam 90 which serves to swing the valve cam about its pivot and temporarily change the relative motions of the valves as the lever 20 is operated. The cam 90 is on a radial arm 91 pivoted on the hub 19 of the lever 20. The wedge is controlled by a lever 92 which may be connected by suitable means not shown to the dash board of the car. The wedge or cam 90 is normally out of engagement and is only used when a particularly heavy mixture is desired temporarily.

Previous to adjusting the various valve-controlling means, I first set the level of the fuel at the tip of the nozzle 2. To do this I remove the cover 13 and the barrel-valve with the hood 5 so that the tip of the nozzle is exposed. I then adjust the float valve as hereinafter described. When this is done, I loosen the lock-nut 30 and turn the needle valve 24 down against the seat 26. Turning the needle valve stem slightly further, the cam follower is raised perceptibly, showing that the valve has reached a bearing. I then rotate the valve stem backward until the follower returns to the cam surface, note the position of the parts, and rotate the valve stem backward about half a turn. Near this position the lock-nut is set after testing for efficiency. It should be understood that the barrel-valve is during this adjustment in the position of low throttle. The adjustment of the needle valve when once accomplished, is practically permanent. The next adjustment is that of the fuel valve cam. To get the best results this should receive attention several times a year. To adjust the fuel valve cam 31, the engine is started and run under maximum, minimum and intermediate loads, the cam being moved until the most efficient running position is found.

To control the level of the liquid, I provide a float valve shown in sectional elevation in Fig. 1. In the carbureter body is a fuel chamber 50 in which is a float 51. In the fuel supply passage 52 is a float valve 54 pressed against its seat by means of a compression spring 55. The latter is supported by means of a screw-plug 56 which is centrally apertured at 57 to receive the valve spindle 58, the aperture 57 being closed by a screw 59. The spindle 58 extends above the valve protruding from the plug 60 on which the valve seat is formed. The float 51 is pivotally connected at 61 to a lever 62 fulcrumed at 63. The lever 62 carries a bearing point or pin 64 in line with the valve spindle to engage the tip 65 of the same. The pin 65 is threaded in the lever and is slotted at 66

so that it may be rotated and moved back and forth in the lever by means of the thread, and a lock-nut 67 holds the pin in adjusted position. In the top wall of the carbureter over the pin 64 is an aperture 69 threaded to receive a plug 70 which is bored axially to receive a pin 71 known in the art as a primer. The pin has a head 72 and an abutment 73 to prevent its escape from the plug, and its length is considerably in excess of that of the plug. A spiral compression spring 74 encircling the pin between its head and the plug, maintains it normally in raised position with the lower abutment against the bottom of the plug. The operation of the primer is apparent. In starting, pressure on the head 72 depresses the lever 62, moving the bearing point 64 against the top of the valve spindle, and opens the float valve to give an initial excess supply of fuel.

It will be noted that the float valve 54 is pressed against its seat by the spring 55, maintaining the fuel passage normally closed. When the fuel in the chamber 50 stands at the desired level, *i. e.* so as to bring the liquid up to the lips of the nozzle 2, the lever 62 is supported with the bearing pin 64 just out of contact with the tip 65 of the spindle 58 of the valve 54. When the level of the liquid falls in the slightest degree, the float will move downward correspondingly, and the valve 54 will be immediately opened by contact of pin 64 with the tip 65, to give the requisite supply of fuel. In this connection it will be noted that the tension of the spring need be only sufficient to lift the valve into position on its seat so that vibration of the float, due to various causes, does not force the valve against its seat, and the bearing surfaces of the valve and seat are not injured in this way. It will also be apparent that to adjust the level of the liquid it is not necessary to change the tension of the spring, such adjustment being obtained by removing the cover to the float chamber and changing the contour of the lever 62, or the equivalent, changing the relative positions of the points 61, 63 and 64.

Another important feature of this device is found in the relative positions of the primary and secondary air passages, or more particularly, their inlet ends. The inlets are located immediately adjacent each other and may be supplied by a single current of air which may be introduced by a single pipe 115 communicating with both inlets or may be otherwise directed. Thus at open throttle when the secondary air is at maximum, the secondary current serves as a carrier for the primary air, thereby increasing the primary air supply at open throttle, with a beneficial result in the increased quantity of hydrocarbon introduced into the mixture at this time.

I have thus described in specific terms cer-

tain preferred embodiments of my invention in order that its operation may be clearly understood. However, the specific terms herein are used in their descriptive rather than in their limiting sense, and the scope of the invention is defined in the claims:

1. In a constant level aspirating carbureter, a valve chamber, a barrel valve therein, a fuel nozzle, the barrel valve having a hood inclosing the fuel nozzle, means for supplying fuel to the nozzle and adjusting the level of the fuel, the barrel valve being conveniently removable to expose the nozzle during adjustment of the fuel level.
2. In a constant level aspirating carbureter, a valve chamber, a barrel valve therein having ports and a constant air passage, a fuel nozzle in the constant air passage, the barrel valve having a hood inclosing the fuel nozzle, means for supplying fuel to the nozzle and adjusting the level of the fuel, the barrel valve being conveniently removable to expose the nozzle during adjustment of the fuel level.
3. In a constant level aspirating carbureter, a valve chamber having a port and a constant air passage, rotating valve, a fuel nozzle in the air passage, the rotating valve having a hood inclosing the fuel nozzle, means for supplying fuel to the nozzle and adjusting the level thereof, the valve chamber having an opening for the removal of the barrel valve, and a removable cover therefor so that the barrel valve may be conveniently removed to expose the fuel nozzle during the adjustment of the level of the fuel.
4. In a constant level aspirating carbureter, a valve chamber, a rotary valve therein having a port and a constant air opening, a hood surrounding the opening, a fuel nozzle within the hood, means for supplying liquid fuel to the nozzle and adjusting the level thereof, the hood being secured to the barrel valve, and the barrel valve and hood being conveniently removable to expose the nozzle for the adjustment of the level of the fuel.
5. In a constant level aspirating carbureter, a valve chamber, a rotary valve therein having an air opening, a fuel nozzle in the air opening, means for supplying liquid fuel to the nozzle and for regulating the level thereof, the valve chamber having an opening for the removal of the barrel valve, the latter being mounted so that it is conveniently removable, a float chamber connected to the nozzle to supply fuel thereto, a float in the chamber and a valve controlled thereby, and means for adjusting the relation of the float and valve to determine the level of the liquid, the float chamber having an opening and a cover therefor which is conveniently removable to expose the mechanism during adjustment so that the float

mechanism and nozzle are both in full view of the operator during the adjustment of the fuel level.

6. A carbureter consisting of two inlet air passages one of which is constantly open and a delivery passage into which both said inlet passages discharge, a fuel nozzle in the constant inlet passage, the two inlet passages meeting beyond the point where the nozzle is located, a barrel valve for controlling the other inlet, a fuel valve controlling the fuel supply moving relatively to the barrel valve and in a line parallel with its axis, means for adjusting the fuel valve to determine its lead which is otherwise constant, and means connecting it to the inlet valve, actuating means whereby the fuel valve is opened with the inlet valve and means for varying the motion of the fuel valve relatively to that of the air valve.

7. A carbureter consisting of two inlet air passages and a delivery passage into which both said inlet passages discharge, a fuel delivery in one inlet passage which passage is constantly open, the passages meeting beyond the point at which the fuel is delivered, a valve for controlling the other inlet, a fuel valve controlling the fuel supply, means for adjusting the fuel valve to determine its lead, and means connecting it to the inlet valve whereby it is opened simultaneously with the inlet valve, and means for adjusting the fuel valve, actuating means to vary the ratio of the valve openings, the fuel valve lead being independent of said adjustment.

8. A carbureter consisting of two inlet air passages and a delivery passage into which both said air passages open, a fuel nozzle in one air passage which passage is constantly open, an air valve controlling the other air passage, a valve in the delivery passage, actuating means connecting said valves to move them both, a fuel valve controlling the nozzle, means connected to the inlet and delivery valve actuating means for opening and closing the fuel valve as the inlet and delivery valves are opened and closed, and means for adjusting said means to vary the relation between the motion of the fuel valve and that of the inlet and delivery valve.

9. In a constant level carbureter, in combination an air passage, a fuel nozzle discharging into the air passage, a valve controlling the air passage, means for actuating the valve, a cam, a follower connected to both valves and engaging the cam to open the fuel valve as the air valve is opened, the cam being substantially cylindrical as to the portion of its surface engaged by the follower when the fuel valve is in initial position and pivoted to swing about the axis of such cylindrical portion.

10. A carbureter consisting of an air pas-

sage, a carbureting passage constantly open, a fuel nozzle in the carbureting passage, a fuel valve coöperating with the nozzle, a valve for controlling the air passage, means 5 connected thereto and operated thereby for opening the fuel valve, said means being adjustable to vary the relative areas of opening of the two valves, and means for adjusting the lead of the fuel valve, the 10 lead being otherwise constant and independent of the aforesaid means for opening the valve.

11. In a carbureter in combination an air 15 passage, a fuel delivery therein, a valve for controlling the air passage, means for actuating said valve, a fuel valve, means controlled by the actuating means for operating the fuel valve, means for adjusting said operating means to vary the relative motions of the valves, means for adjusting the 20 lead of the fuel valve, and means for temporarily varying the arrangement of the valve operating means to change the relations of the valve openings to compensate 25 for temporary alteration of running conditions.

12. In a carbureter in combination an air 30 passage, a valve controlling the same, means for actuating the said valve, a fuel delivery in the air passage, a fuel valve, a cam, a follower therefor connected to the actuating 35 means and to the fuel valve to operate the same, means for adjusting the throw of the cam to vary the relative motions of the valves, means for adjusting the fuel valve 40 to determine its lead and other means for temporarily increasing the opening of the fuel valve relatively to that of the air valve at all open positions greater than the least opening of the air valve without affecting 45 the lead of the fuel valve to compensate for changes of running conditions.

13. In a carbureter in combination an air 45 passage, a valve controlling the same, a fuel delivery in the air passage, a fuel valve, a cam pivotally mounted, actuating means for one valve, a follower on the other valve engaging the cam and connected to the actuating means to move the follower over the 50 cam to operate that valve, means for adjusting the cam about its pivot to vary its throw, and other means for swinging the cam to compensate for temporary changes of running conditions.

55. 14. In a carbureter in combination an air passage, a valve controlling the same, a fuel delivery in the air passage, a fuel valve, a cam pivotally mounted, means for actuating one valve, a follower on the other valve engaging the cam and connected to the operating means to be moved over the cam to 60 operate that valve, means for adjusting the cam about its pivot to vary its throw, other means in the form of a wedge, and means

for advancing the same beneath the cam to 65 swing the cam to give an increased opening of the fuel valve and compensate for temporary changes of running conditions.

15. In a carbureter the combination of a carbureter chamber having an air inlet passage and a mixture outlet passage arranged one on each side of the carbureting chamber opposite each other, a fuel nozzle supplying fuel to the carbureting chamber and centrally located between the air inlet and 75 mixture outlet, an independent air inlet surrounding the fuel nozzle, a cylindrical throttle valve having oppositely located ports, one controlling the air inlet and the other 80 the mixture outlet, the gas outlet port having a lead of a size corresponding to the size of the independent air inlet surrounding the fuel nozzle.

16. In a carbureter the combination of a carbureting chamber having an air inlet and 85 mixture outlet arranged axially of each other and on opposite sides of the carbureting chamber, a fuel supply nozzle arranged centrally of the carbureting chamber and midway between the air inlet and mixture outlet, independent air supply surrounding the fuel nozzle and entering the carbureting chamber, this air supply drawing air from the main air inlet beyond the throttle valve, 90 a throttle valve cylindrical in form and having oppositely disposed ports, one controlling the air inlet and the other the mixture outlet, the mixture outlet port having a lead-notch in one side of a size corresponding 95 to the size of the independent air inlet surrounding the fuel nozzle.

17. In a carbureter the combination of a carbureting chamber, cylindrical in form and having a vertical axis, and provided with an air inlet port on one side and a mixture outlet port on the other side, said ports being axially arranged, said axis being at right angles to the axis of the carbureter chamber, the air inlet port being divided into two parts, one of which enters the carbureting chamber axially of the outlet port while the other is constantly open and enters the carbureting chamber through its bottom axially of the carbureting chamber, 105 a fuel nozzle located axially of the carbureting chamber entering it through the bottom and centrally of the air inlet port, a cylindrical throttle valve located within the carbureting chamber and having inlet and outlet ports in its sides oppositely located, 110 a baffle-hood located within the carbureting chamber and over the fuel nozzle and its surrounding air inlet.

18. In a constant level carbureter having 115 a delivery passage, two separate and distinct air passages, one being a constantly open primary air passage, the other a secondary air passage, a barrel valve for con-

trolling the delivery and secondary air passage, a fuel nozzle in the delivery end of the constant air passage, a fuel valve, a cam of arcuate form concentric with the fuel valve, a follower for the cam connected to the fuel valve to move the latter, the cam being pivotally mounted and means for adjusting the cam about its pivot to vary the effective throw thereof.

19. In a constant level carbureter, a constantly open primary air passage, a secondary air passage, a carbureting chamber and an outlet passage, the primary and secondary air passages having their delivery ends in the carbureting chamber, a fuel nozzle in the outlet end of the primary air passage, a barrel valve having ports controlling the secondary air passage and the outlet passage, an arcuate cam pivotally mounted, a fuel valve, a follower for the cam connected to the fuel valve and to the barrel valve to rotate with the barrel valve and move over the cam, opening and closing the fuel valve as the barrel valve ports are opened and closed, and means for adjusting the cam about its pivot to vary its throw and hence to vary the throw of the needle valve in proportion to the barrel valve.

20. In a constant level carbureter, a primary air passage, a secondary air passage, a carbureting chamber and a delivery passage, the primary and secondary air passages having their delivery ends in the carbureting chamber, a fuel nozzle in the outlet end of the primary air passage, a barrel valve enclosing the fuel nozzle and the delivery end of the primary air passage and having ports controlling the secondary air passage and the delivery passage, an arcuate cam pivotally mounted, a fuel valve, a follower for the cam connected to the fuel valve and to the barrel valve to rotate with the barrel valve and move over the cam, opening and closing the fuel valve as the barrel valve ports are opened and closed, and means for adjusting the cam about its pivot to vary its throw and hence to vary the throw of the needle valve in proportion to the barrel valve.

21. In a constant level carbureter, a constantly open primary air passage, a secondary air passage, a carbureting chamber and an outlet passage, the primary and secondary air passages having their delivery ends in the carbureting chamber, a fuel nozzle in the outlet end of the primary air passage, a barrel valve having a port controlling the secondary air passage, an arcuate cam pivotally mounted, a fuel valve, a follower for the cam connected to the fuel valve and to the barrel valve to rotate with the barrel valve and move over the cam, opening and closing the fuel valve as the barrel valve ports are opened and closed,

and means for adjusting the cam about its pivot to vary its throw and hence to vary the throw of the needle valve in proportion to the barrel valve, the cross-section of the cam being curved so that the cam path is identical in form in all positions of adjustment.

22. In a constant level carbureter, a constantly open primary air passage, a secondary air passage, a carbureting chamber and an outlet passage, the primary and secondary air passages having their delivery ends in the carbureting chamber, a fuel nozzle in the outlet end of the primary air passage, a barrel valve having ports controlling the secondary air passage and the delivery passage, the delivery port having a lead opening equal in area to the area of the constant air passage, an arcuate cam pivotally mounted, a fuel valve, a follower for the cam connected to the fuel valve and to the barrel valve to rotate with the barrel valve and move over the cam, opening and closing the fuel valve as the barrel valve ports are opened and closed, and means for adjusting the cam about its pivot to vary its throw and hence to vary the throw of the needle valve in proportion to the barrel valve.

23. In a constant level carbureter, a U-shaped constantly open primary air passage, a fuel nozzle in the delivery end of the passage, a secondary air passage connecting the ends of the U-shaped passage, a barrel valve controlling the secondary air passage, a follower pivotally mounted on the barrel valve and connected to the fuel valve, a stationary cam mounted for adjustment in a plane parallel to the axis of the barrel valve, the follower being adapted to coöperate with the cam and means for adjusting the cam to vary the motions of the fuel and air valves.

24. In a carbureter, a fuel valve and a barrel valve, a stationary cam mounted on a pivot substantially at right angles to the radius of the barrel valve drawn to the center of the pivot, the cam being of arcuate form concentric about the axis of the barrel valve, means for adjusting the cam about its pivot, a follower for the cam connected to the barrel valve to rotate therewith and connected to the fuel valve to move the latter as the barrel valve is rotated.

25. In a carbureter, a fuel valve and a barrel valve, a stationary cam mounted on a pivot substantially at right angles to the radius of the barrel valve drawn to the center of the pivot, the cam being of arcuate form concentric about the axis of the barrel valve, means for adjusting the cam about its pivot, the cross-section of the cam being curved so as to give a path of substantially uniform contour as the cam is adjusted, the

only variation of the path being change of angle due to the adjustment, a follower for the cam connected to the barrel valve to rotate therewith and connected to the fuel valve to move the latter as the barrel valve is rotated.

Signed by me at city of Baltimore, State

of Maryland, this 14th day of February 1911.
